UNITED STATES PATENT OFFICE

2,392,223

METHOD OF MAKING BARBED WIRE STRUCTURES

Alan E. Brickman, New Haven, Conn., assignor to
The American Steel and Wire Company of New Jersey, a corporation of New Jersey

Application June 3, 1943, Serial No. 489,514

6 Claims. (Cl. 140—58)

This invention relates to a method of making barbed wire structures. Barbed wire is used as obstacles against the passage of men or beasts. At present a large amount of barbed wire is used in making barb wire entanglements to prevent the passage of foot troops. The standard wire used is the common two-wire type No. 12 A. S. & W. gage with four-point barbs spaced approximately 4 inches apart. This wire is shipped to the front on reels weighing 50 to 100 pounds where the barbed wire entanglements are constructed from a multiple of barbed wire strands which in most instances are arranged in parallel rows. If one or two of the bottom wires are cut, the enemy can pass through the entanglement.

It is an object of this invention to provide a barbed wire which is much lighter in weight than the present standard barbed wire.

Another object is to provide a barbed wire mat which may be used in place of a plurality of strands of barbed wire.

A further object is to provide a novel method of making barbed wire structures.

These and other objects will be more apparent after referring to the following specification and attached drawings, in which:

Fig. 1 shows a welded wire fabric from which the barbed wire is made;

Fig. 2 shows the completed barbed wire of the present invention;

Fig. 3 is an end view of the barbed wire of Fig. 2;

Fig. 4 is a view of the barbed wire mat of the present invention;

Fig. 5 shows one form of barb used in the present invention;

Figs. 6 and 7 disclose modifications of the barb;

Figs. 8 and 9 show the use of the mat in building obstacle fences;

Figs. 10 to 13, inclusive, show various modifications and adaptations of the barbed wire mat.

Referring more particularly to the drawings, the reference numeral 2 indicates a welded wire fabric from which the barbed wire structure of the present invention can be made. The welded wire fabric 2 consists of a plurality of longitudinal strands of wires 4 to which are welded a plurality of cross wires 6. The longitudinal wires 4 have tension crimps 8 for maintaining the barbed wire taut under conditions of contraction or expansion. If desired, these tension crimps may be dispensed with.

A single strand barbed wire is made as follows:

A welded wire fabric 2, of the desired weight having the spacing of the cross wires the same

as the desired spacing of the barbs, is provided. The cross wires are cut on a bias as shown at 10 in Fig. 1 and the cut wires are bent to form a substantially V-shaped barb 12. Each cross wire is bent in a direction opposite to that of the wires adjacent thereto as clearly shown in Figs. 2 and 3.

In making a barbed wire mat, such as shown in Fig. 4, substantially the same method is followed. Part of the longitudinal wires 14 are cut on a bias and bent into barbs 18 which extend from the mat in one direction. The completed mat consists of a plurality of longitudinal wires 14 and a plurality of cross wires or pickets 16 to which barbs 18 are fastened. This mat may be used in fields and roads to puncture pneumatic tires of enemy planes or land vehicles.

The barbs may assume various shapes. As shown in Fig. 5, the barb 20 is bent on a sharp radius around the cross wire 16. The barb 22 of Fig. 6 is bent around the wire 16 on a larger radius and extends upwardly at a sharper angle than the barb 20. The barb 24 of Fig. 7 has a flat portion 26 and extends upwardly at substantially the same angle as barb 22.

Fig. 8 shows how the mats are utilized to make a double apron fence. A mat 28 with the barbs facing upwardly is laid against one side of a standard fence post 30 and a second mat 28 is laid against the post 30 from the other side. The bottoms of the mats 28 are anchored by means of pegs 32.

Fig. 9 discloses the use of the mats in a moat fence. In making a moat fence U-type line posts 34 are arranged in parallel rows. On the row of posts nearest the enemy, a mat 28 is fastened so that it extends for some distance above the top of the posts. The mat is then bent back in a direction away from the enemy at an angle of about 45°. A second mat 28 is fastened to the other row of posts with its top approximately on a level with the top of the posts and the bottom of the mat is bent toward the first row of posts at an angle of about 45°. Both mats have their barbs extending toward the enemy.

Fig. 10 shows a mat 36 used as an overhang on a fence 38. This mat differs from the previous mat in having the barbs welded to the longitudinal strands. Fig. 11 is similar to Fig. 10, but discloses a mat 28 having the barbs welded to the cross wires.

Fig. 12 discloses a special type of mat 42 which has two lines of barbs 44 fastened to the top of the cross wires or pickets 46. This particular type of mat is used as a fence and the two lines

of barbs 44 prevent cattle from leaning against the top strands of the fence.

Fig. 13 discloses a mat 48 which may be used as a fence or as part of a trap. The top strand is cut and bent downwardly to form the barbs 50 which discourage climbing or any form of top wire loading.

While various modifications of the invention have been shown and described, it will be apparent that other modifications may be made without departing from the scope of the attached claims.

I claim:

1. The method of making a barbed wire structure which comprises providing a welded fabric having a plurality of wires extending in one direction welded to a plurality of wires extending transversely of said first wires, severing at least one of said transverse wires between said first named wires, and bending the cut wires into substantially V-shaped barbs. 15

2. The method of making single strand barbed wire which comprises providing a welded fabric having a plurality of wires extending in one direction welded to a plurality of wires extending transversely of said first wires, the spacing of the cross wires being the same as the desired spacing of the barbs, cutting at least one of the transverse wires on a bias between the longitudinal wires, and bending the cross wires into substantially V-shaped barbs. 25

3. The method of making single strand barbed wire which comprises providing a welded fabric having a plurality of wires extending in one direction welded to a plurality of wires extending 30

transversely of said first wires, the spacing of the transverse wires being the same as the desired spacing of the barbs, cutting the transverse wires on a bias between the first named wires, and bending the transverse wires into substantially V-shaped barbs.

4. The method of making single strand barbed wire which comprises providing a welded fabric having a plurality of wires extending in one direction welded to a plurality of wires extending transversely of said first wires, the spacing of the transverse wires being the same as the desired spacing of the barbs, severing the transverse wires between the first named wires, and bending the transverse wires into substantially V-shaped barbs, each transverse wire being bent in a direction opposite to the wire adjacent thereto. 15

5. The method of making a barbed wire mat which comprises providing a welded fabric having a plurality of wires extending in one direction welded to a plurality of wires extending transversely of said first wires, severing part of said transverse wires between said first named wires, and bending the cut wires into substantially V-shaped barbs. 20

6. The method of making a barbed wire mat which comprises providing a welded fabric having a plurality of wires extending in one direction welded to a plurality of wires extending transversely of said first wires, cutting part of said transverse wires on a bias between said first named wires, and bending the cut wires into substantially V-shaped barbs extending in one direction from the surface of the mat. 25

ALAN E. BRICKMAN.
